FIRE ALARM APPARATUS

Walter J. Thorsen, El Cerrito, Calif.

Application May 10, 1957, Serial No. 658,373

3 Claims. (Cl. 340—227)

This invention relates to a new type of closed circuit fire alarm system in which the circuit is broken when a fire occurs. More specifically the system incorporates a method of utilizing closed circuit fire detectors in conjunction with one or more single or compound thermal switches which, in case of a fire, act to intermittently actuate an alarm signalling device such as a bell, buzzer or the like.

Notwithstanding modern methods of fire prevention, fires cause almost one billion dollars' worth of damage yearly. Much of this loss could be prevented by the prompt discovery of these fires, which, like cancer, if caught early enough can be brought under control before too much damage has occurred.

Many fire warning systems are available, but all are too expensive for the average home owner, particularly because they necessitate the use of magnetic relays. Moreover the open circuit type of fire detector, which is used with most known systems, is often faulty in operation due to contact contamination problems, and requires an excessive amount of wire.

A particular advantage of the system of this invention is that it utilizes thermal switches which have excellent electrical characteristics and are low in cost in comparison with magnetic relays. Another advantage is that the invention utilizes a closed circuit system which eliminates contact contamination problems and which will give a signal when the circuit is accidentally opened or broken. Also, the alarm system of this invention offers the advantage of a flashing or intermittent alarm signal, which is more likely to awaken the occupant of a building than a steady signal as provided in known systems. A further advantage of the present invention is that existing bell or chime transformers can be used as a source of power and a separate power source as required with known alarm systems is eliminated.

I now have discovered a new system of fire detection which incorporates inexpensive and reliable closed circuit fire detectors mounted strategically in the areas desired to be protected, connected in a single loop closed circuit to a control unit, in turn connected to an existing power transformer and an alarm signalling device. The control unit causes a small current to flow through this loop. When a fire occurs, the nearest fire detector opens the loop circuit and interrupts the current flowing through it. This actuates one or more single or compound thermal switches in the control unit in such a manner as to intermittently switch the alarm signalling device on and off. When the fire is over and the detector is restored to its original condition the current will again flow through the closed loop circuit, causing the control unit to switch off the signalling device.

It is accordingly a primary objective of my invention to provide a simple, more reliable, and less expensive fire alarm system for the detection of fires than heretofore possible.

Another object is to provide such a system wherein

2

highly reliable, inexpensive closed circuit fire detectors are used.

A further object is to provide a single loop closed circuit for the fire detectors.

5 An additional object is to incorporate one or more single or compound thermal switches in the control unit—such switches being practically indestructible and of extremely low cost.

Still another object is to provide a special circuit 10 for the above switch or switches such that a flashing alarm signal will result.

A further object is to provide a control unit which utilizes the low voltage transformer and the doorbell already in existence in the building, thus greatly reducing 15 material and installation costs.

A further object is to provide an alarm system which is so simple to install that any "do-it-yourself" person may install the whole system in an afternoon.

Other objects of my invention will become apparent 20 from a consideration of the following description, taken in conjunction with the attached drawings of which Figures 1 and 2 are circuit diagrams of two embodiments of my invention.

As illustrated in Figure 1 my first embodiment consists of fire detectors 1 connected in a series loop circuit A by wires 2, which are in turn connected to control unit B, which in turn is connected to existing doorbell C and existing power source, transformer D. Fire detectors are of conventional construction, including two 25 conduction elements connected at their ends by a deposit of fusible metal. In the event of a fire, the fusible metal melts, breaking the contact between the conductors. Doorbell C may take the form of a conventional device of the type equipped with a closed circuit solenoid coil. Transformer D is a conventional bell transformer.

Transformer D is connected to bell C by wire 3. Control unit B is connected to transformer D by wire 4 and to bell C by wire 5. Wire 5 is connected to wire 6 which is connected to contact point 7 and loop wire 2. 30 Wire 4 is connected to wire 8 which is connected to one end of a low resistance heating coil 9 which is wound around bimetal strip 10. The other end of heating coil 9 is grounded to bimetal strip 10. Contact 11 is attached to bimetal strip 10. One end of high 35 resistance heating coil 12 is also grounded to bimetal strip 10 and its other end is attached to loop wire 2.

The operation of the system is as follows: 40 Transformer D impresses a voltage, via wire 3 and bell C, across wires 4 and 5. The same voltage is therefore impressed across wires 6 and 8 in control unit B. This causes a small current to flow through the detector 45 loop wires 2 and detectors 1, high resistance coil 12, low resistance coil 9, and wire 8. The total resistance of coils 9 and 12 is sufficiently high that the current flow through bell C is too low to cause it to ring. However the heat produced in coil 12 warms bimetal strip 10 enough to flex it upwardly to maintain contacts 7 and 11 in the open position. (In the absence of heat strip 10 is biased downward to close contacts 7 and 11.) Very 50 little heat is given off by coil 9 because it has a low resistance in comparison with coil 12.

When a fire occurs near a fire detector 1 the current 55 flowing through the detector loop wiring 2 is interrupted. This interrupts the flow of current through coils 9 and 12 and causes bimetal strip 10 to cool in a few seconds, thereby deflecting strip 10 downwardly and closing contacts 7 and 11. This causes a heavy current to flow 60 through wire 3, bell C, wires 5 and 6, contacts 7 and 11, a portion of bimetal strip 10, coil 9, and wires 8 and 4, thus causing the bell to ring. This current is now sufficiently heavy to cause appreciable heat to be generated in coil 9. Bimetal strip 10 is thereby warmed up again in

a few seconds, flexing upwardly and opening contacts 7 and 11. This interrupts the current flowing through bell B and stops it from ringing. Simultaneously the current flowing through coil 9 is interrupted and thus bimetal strip 10 again cools in a few seconds, causing bell B to ring again, etc. Thus an intermittent or flashing alarm signal is produced when a fire occurs near any fire detector 1. When loop A is again restored to its initial closed condition, coil 12 again heats bimetal strip 10 sufficiently to maintain contacts 7 and 11 in the open position, terminating the alarm signals.

As illustrated in Figure 2 my second embodiment consists of fire detectors 1 connected in a series loop circuit A by wires 2, which are in turn connected to control unit B', which is in turn connected to existing doorbell C and existing source of power, transformer D.

Transformer D is connected to bell C by wire 3. Control unit B' is connected to transformer D by wire 4 and bell C by wire 5. Wire 5 is connected to wire 13, in turn connected to bolt 14 which clamps bimetal strip 15 to insulating mount 16. Electrical contact is made between bolt 14 and bimetal strip 15. One end of resistance wire heating coil 17 is connected to bolt 14 and the other end to bolt 24. One end of wire 19 is connected to bolt 14 and the other to one end of resistance wire coil 20. The other end of coil 20 is connected to wire 21 which is connected to loop wire 2. Contacts 26 and 22 are connected to bimetal strips 15 and 18, respectively. Loop wire 2 is connected to wire 23, in turn connected to bolt 24 which clamps bimetal strip 18 to insulating mount 16. Electrical contact is made between bolt 24 and bimetal strip 18. Bolt 24 is connected to wire 25, which is in turn connected to wire 25, which is in turn connected to wire 4.

The operation of the system is as follows:

Transformer D impresses a voltage, via wire 3 and bell C, across wires 4 and 5 attached to control unit B'. The same voltage is therefore impressed across wires 13 and 25 in control unit B'. This causes a small current to flow through wire 13, bolt 14, wire 19, coil 20, wire 21, detector loop wiring 2 and detectors 1, wire 23, bolt 24, wire 25, and coil 17. The parallel resistance of coils 17 and 20 is high enough so that the current flow through bell C is too low to cause it to ring. The heat produced in coils 17 and 20 warms up bimetal strips 15 and 18, causing them both to flex away from base 16, that is, downwardly and the contacts remain open. (In absence of any heat the contacts are likewise open.)

When a fire occurs near a fire detector 1 the current flowing through the detector loop wiring 2 is interrupted. This interrupts the flow of current through coil 20 and causes bimetal strip 18 to cool in a few seconds, thereby flexing strip 18 upwardly and closing contacts 22 and 26. This shorts out bolts 14 and 24 and causes bell C to ring. The shorting action simultaneously drops the voltage impressed across coil 17 to zero. Bimetal strip 15 cools in a few seconds, flexing upwardly and opens contacts 22 and 26. This causes bell C to stop ringing and simultaneously impresses the voltage across coil 17 again. The resulting heat causes contacts 22 and 26 to close again in a few seconds and bell C rings again etc. Thus, an intermittent or flashing alarm signal is produced when a fire occurs near any detector 1. When loop A is restored to its initial closed condition coil 20 again heats bimetal strip 18 sufficiently to maintain contacts 22 and 26 in the open position, terminating the alarm signals.

I claim as my invention:

1. A fire alarm system comprising a closed series circuit of a power source, an alarm unit, a loop containing at least one fire detector unit, a high resistance heating coil, and a low resistance heating coil, said coils being in heat-transfer relationship to a thermo-responsive armature, a pair of contacts, one contact connected to said alarm unit, the other contact being on said armature and

connected through said armature and low resistance heating coil to said power source, said coils and armature being operative to maintain the contacts in open position under normal temperature conditions at which the circuit remains closed and in the event of unusual high temperature conditions which cause opening of a fire detector unit being operative to intermittently close said contacts whereby to intermittently connect said alarm unit directly to the power source to provide an intermittent alarm signal.

10 2. A fire alarm system comprising a closed series circuit of a power source, an alarm unit, a loop containing at least one fire detector unit, a high resistance heating coil, a low resistance heating coil, said coils being in heat-transfer relationship to a thermo-responsive armature, one end of said high resistance coil being connected to said loop, the other being connected to said armature, one end of said low resistance coil being connected to said armature, the other end being connected to said power source, a pair of contactors, one being connected to said alarm unit, the other being on said armature and connected through said armature and low resistance coil to said power source, whereby under normal temperature at which the circuit remains closed current flows through said alarm unit, loop and coils in series, the series resistance of the coils being sufficient to prevent actuation of said alarm unit, the heat provided by said coils being sufficient to deflect the armature to maintain the contacts in open position, and in the event of unusual high temperature conditions which cause opening of a fire detector and 15 subsequent disconnection of the coils from the source of power, cooling of the armature causing closing of the contacts whereby the alarm unit is connected to the power source through the low resistance coil, the subsequent heating of the armature by this coil causing opening of 20 the contacts, the process of opening and closing of the contacts being intermittently repeated as long as the loop circuit remains open.

25 3. A fire alarm system comprising a closed series circuit of a power source, an alarm unit, a loop containing at least one detector unit and a first heating coil, said coil being in heat transfer relationship to a first thermo-responsive armature, said armature being connected to said power source and being provided with a contact, a second heating coil in parallel to said circuit 30 one end connected to said power source the other to said alarm unit, said coil being in heat transfer relationship to a second thermo-responsive armature, said armature being connected to said alarm unit and being provided with a contact, said armatures being deflectable by heat in the same direction and being so positioned that when the loop circuit remains closed, as at normal temperatures, the heating effect of both coils deflect both armatures in the same direction maintaining the contacts in open position whereas when the loop circuit is opened, as at unusually 35 high temperatures, current to the first coil is interrupted resulting in deflection of the first armature toward the second armature thus closing the contacts and connecting the alarm unit directly to the power source, and short-circuiting the second coil which in turn causes cooling and 40 deflection of the second armature away from the first, re-opening the contacts whereby a circuit from the power source to the alarm unit through the second coil is re-established and the second coil again heats the second armature, deflecting it to close the contacts and to connect the alarm unit directly to the power source whereby to provide an intermittent alarm signal as long as the loop circuit is open.
